DESIGN FOR A DISTRIBUTION BOX FOR ELECTRIC FENCE INSTALLATIONS

Sidney A. Moore, Milwaukee, Wis., assignor to
The Prime Manufacturing Company, Milwaukee,
Wis., a corporation of Wisconsin

Application February 11, 1938, Serial No. 75,073

Term of patent 3½ years

To all whom it may concern:

Be it known, that I, Sidney A. Moore, a citizen of the United States, residing at Milwaukee, in the county of Milwaukee and State of Wisconsin, have invented a new, original, and ornamental Design for a Distribution Box for Electric Fence Installations, of which the following is a specification, reference being had to the accompanying drawing, forming part thereof.

Figure 1 is a front perspective view of a distribution box showing my new design; and

Figure 2 is a rear perspective view thereof.

I claim:

The ornamental design for a distribution box for electric fence installations, as shown.

SIDNEY A. MOORE.
